UNITED STATES PATENT OFFICE.

WAKEFIELD PHINNEY, OF REDLANDS, CALIFORNIA.

COMB.

No. 841,175.

Specification of Letters Patent.

Patented Jan. 15, 1907.

Application filed October 10, 1905. Serial No. 282,125.

To all whom it may concern:

Be it known that I, WAKEFIELD PHINNEY, a citizen of the United States, residing at Redlands, in the county of San Bernardino 5 and State of California, have invented a new and useful Comb, of which the following is a specification.

The invention relates to improvements in combs.

10 The object of the present invention is to improve the construction of combs and to provide a simple, inexpensive, and efficient comb designed for applying hair and scalp tonic to the scalp of a person and capable of 15 being firmly gripped and operated with one hand, both to manipulate the comb and control the discharge of the tonic or other liquid.

A further object of the invention is to provide a comb of this character adapted to fit 20 the head and capable of discharging the tonic or other liquid directly on the scalp at intervals in the desired quantity.

With these and other objects in view the invention consists in the construction and 25 novel combination and arrangement of parts hereinafter fully described, illustrated in the accompanying drawings, and pointed out in the claims hereto appended, it being understood that various changes in the form, proportion, size, and minor details of construction 30 within the scope of the claims may be resorted to without departing from the spirit or sacrificing any of the advantages of the invention.

35 In the drawings, Figure 1 is a side elevation of a comb constructed in accordance with this invention. Fig. 2 is a longitudinal sectional view of the same. Fig. 3 is a transverse sectional view on the line 3-3 of Fig. 2. 40 Fig. 4 is a detail perspective view of the bulb and the tube for filling the bulb.

Like numerals of reference designate corresponding parts in all the figures of the drawings.

45 1 designates a comb designed for applying hair and scalp tonic to the head and provided with a longitudinal opening or passage 2 and having small bores or passages 3, extending from the main passage or opening 2 through 50 the teeth 4 of the comb to the extreme points thereof, so that the tonic or other liquid will be discharged directly on the scalp. The body of the comb is straight, and the teeth are arranged at regular intervals and gradually taper in length from the ends of the comb 55

to the center to arrange their points in a concavely-curved row to conform to the configuration of the head of a person. The teeth are enlarged and preferably tapered, as shown, and the comb is provided at the back 60 with a projecting substantially segmental grip or handle 5 to enable it to be firmly grasped and securely held by one hand. The grip or handle, which consists of a thin upwardly-projecting flange, extends from one 65 end of the comb to a point about the center thereof, and it extends outward in a longitudinal direction slightly beyond the series of teeth of the comb; but it may be made of any desired size, as will be readily understood. 70 The outer end of the handle is arranged coincident with one end of the body of the comb, the teeth of the comb terminating a short distance from such end of the body.

The longitudinal opening or passage 2, 75 which is straight, extends from one end of the body of the comb and terminates short of the other end of the same and is closed at the end 6. The other end of the opening or passage 2 is slightly enlarged and is interiorly threaded 80 to receive an exteriorly-threaded nipple or tube 7 of a compressible bulb 8, which in practice is designed to be of sufficient size to hold one application of a tonic or other liquid. In using the device the handle or grip 85 5 is grasped with one hand and the comb is moved through the hair over the scalp with the points of the teeth bearing against the same, and the bulb is compressed by the hand holding the comb during such operation to 90 secure the desired discharge of the tonic or other liquid. By these means the tonic or other liquid may be applied directly to the scalp, which may be thoroughly irrigated without unnecessarily saturating the hair of 95 the patient.

The bulb may be readily filled by compressing it and then immersing the nipple or tube in a shallow receptacle containing the tonic or other liquid. The expansion of the bulb 100 will suck into it the desired quantity of the liquid. The liquid may be conveniently obtained from a bottle or other vessel having too small a neck to permit the bulb to be inserted in it by employing a tube 9, which has 105 one end interiorly threaded to receive the exteriorly-threaded tube or nipple 7 of the bulb. After the bulb has been filled the tube 9, which is preferably tapered, is removed and the bulb is attached to the comb. 110

Having thus fully described my invention, what I claim as new, and desire to secure by Letters Patent, is—

1. A comb of the class described consisting of a straight body and teeth extending downward from the body, said body and teeth having connecting-passages, a handle extending longitudinally of and projecting from the upper edge of the body of the comb and located directly above the said teeth and having its outer end coincident with one end of the said body, and means for forcing a liquid through the passages of the comb, said means being located at one end of the handle, and the said means and handle being arranged to be simultaneously grasped with the hand, whereby the liquid may be forced through the passages of the comb by the hand holding the same.
2. A comb of the class described consisting of a straight body provided with a handle

extending along and projecting upward from the said body and having its outer end coincident with one end of the said body, and tapering teeth having their points arranged in a concaved row, said comb being provided in its body and teeth with connecting-passages, and means located at one end of the body of the comb for forcing a liquid through the passages, said means and handle being arranged to be simultaneously grasped with one hand, whereby the liquid may be forced through the passages of the comb by the hand holding the same.

In testimony that I claim the foregoing as my own I have hereto affixed my signature in the presence of witnesses.

WAKEFIELD PHINNEY.
